UNITED STATES PATENT OFFICE.

HIAL D. BROOKE, OF SAN FRANCISCO, CALIFORNIA, ASSIGNOR TO
WILLIAM KOLMAN, JAMES W. BUTLER, AND COURTNEY VAN
RIPER, OF SAN FRANCISCO, CALIFORNIA.

HOLLOW CEMENT BUILDING-BLOCK.

No. 800,067.

Specification of Letters Patent.

Patented Sept. 19, 1905.

Application filed November 4, 1904. Serial No. 281,464.

To all whom it may concern:

Be it known that I, HIAL D. BROOKE, a citizen of the United States, residing at San Francisco, in the county of San Francisco and State 5 of California, have invented a new and useful Improvement in Hollow Cement Building-Blocks, of which the following is a specification.

This invention relates to cement building-blocks, and has for its object to produce a comparatively simple inexpensive device of this character in which a free circulation of air through a wall or other structure composed of the blocks will be maintained, one 15 wherein expansion and contraction are minimized and one in which the individual blocks will be securely locked in position in the wall regardless of the cement or other binding material employed.

With these and other objects in view the invention comprises the novel features of construction and combination of parts more fully hereinafter described.

In the accompanying drawings, Figure 1 is 25 a perspective view, partly in section, of a portion of a wall constructed of my improved blocks. Fig. 2 is a perspective view of one of the blocks.

Referring to the drawings, and particularly 30 Fig. 2, it will be seen that the improved block comprises a pair of parallel side portions or sections 1, arranged in spaced relation and connected adjacent their ends by transverse connecting portions or webs 2, each having 35 its outer face concaved to produce a normally vertical groove or channel 3, the parts 1 and 2 serving conjointly to bound an enlarged air opening or passage 4, provided centrally and vertically through the block. The side sections 1 of the block have formed upon their 40 normally lower edges longitudinally-extending ribs or tongues 5, preferably of substantially semicircular form in cross-section, while formed in the normally upper edges of the sections are longitudinal grooves or channels 6, of a cross-sectional form, corresponding to 45 that of the tongues and adapted in practice to receive the latter, there being formed in the upper and lower edges of the webs 2, at a 50 point centrally between the sections 1, semi-

circular grooves or channels 7, arranged parallel with the longitudinal axis of the block and communicating at their ends with the passages and opening 4, respectively.

In practice when a number of the blocks are 55 assembled for erecting a wall, as illustrated in Fig. 1, the grooves 6 in the blocks composing one course of the wall receive the tongues 5 of the superposed blocks forming the contiguous course of the wall, thus securely locking the individual blocks in position. It is to be observed that the blocks in each course 60 are arranged in endwise alinement with their adjacent ends abutting, whereby the tongues 5 and grooves 6 will be practically continuous 65 throughout the entire length of the wall and the channels 3 in the meeting ends of the blocks conjointly produce vertical air flues or passages. It is further to be noted that the meeting ends of a pair of blocks in one course 70 of the wall are disposed between the ends of a block in a contiguous course, whereby the locking of the blocks in the wall is more effectually accomplished and the air passages or flues formed by the channels 3 are disposed 75 above and between the ends of the opening 4 in the underlying block, while at the same time the air-passages 7 insure the free circulation of air from one opening 4 to another and also from a pair of adjacent openings 4 80 into and through the passages 3.

From the foregoing it is apparent that I produce a simple building-block which in practice will sufficiently perform its functions to the attainment of the ends in view, it being understood that minor changes in the details herein set forth may be resorted to without departing from the spirit of the invention.

Having thus fully described the invention, what is claimed as new is

A hollow building-block comprising a pair of spaced side sections and transverse connecting-webs producing an enlarged central opening in the block, said webs being provided at their outer faces and at the ends of the block 85 with grooves or channels disposed transversely of the latter and upon their upper and lower edges with grooves extending in a direction longitudinal of the block, the latter grooves 90 being situated at a point between the side sec- 100

tions and adapted to communicate with the end channels and central opening, and a longitudinally-extending tongue provided on one side edge of each of the sections, the opposite edge of each section being provided with a corresponding longitudinal groove.

5 In testimony whereof I have hereunto signed

my name to this specification in the presence of two subscribing witnesses.

HIAL D. BROOKE.
